Atty.

UNITED STATES PATENT OFFICE.

ALBERT D. GROVER, OF NEW YORK, N. Y., ASSIGNOR TO AUTOSALES CORPORATION, A CORPORATION OF NEW YORK.

VENDING MACHINE.

Original application filed May 8, 1918, Serial No. 233,194. Divided and this application filed June 28, 1921. Serial No. 480,998.

To all whom it may concern:

Be it known that I, ALBERT D. GROVER, a citizen of the United States, and a resident of New York, in the county and State 5 of New York, have invented certain new and useful Improvements in Vending Machines, of which the following is a specification.

My invention relates to vending machines 10 and has for its object the provision of a machine embodying certain improvements and advantages over machines of this class heretofore constructed.

My invention is particularly applicable 15 to multiple-compartment vending machines of the large type—that is to say, those which are operated in public places, like streets, railroad stations, and the like. Each of the magazines of my new machine 20 has associated therewith a hand-operable delivery mechanism. These mechanisms are mounted separately and independently 25 of each other, so that each mechanism may be removed from the machine as a unit without disturbing the other delivery mechanisms. In this way, should any one 30 of these separate delivery mechanisms get out of order, it is easily replaced by another. When these delivery mechanisms are 35 in place on the machine, they form part of the front wall of the casing, and so dispense with the necessity of a separate outer plate to cover these mechanisms, as is found in many machines heretofore constructed.

Another object of my invention is to provide certain improvements in a coin-controlled delivery mechanism employing a 40 slideable coin-plate and a plunger connected therewith.

The objects and advantages of my invention will become apparent from a detailed description of the accompanying drawings, in which—

Fig. 1 shows a plan view of a portion 45 of a vending machine embodying my invention;

Fig. 2 is a vertical section approximately on line 2—2 of Fig. 1, looking in the direction of the arrows;

Fig. 3 is a transverse cross-section 50 through one of the delivery mechanisms approximately on line 3—3 of Fig. 1, looking in the direction of the arrows;

Fig. 4 is a vertical cross-section approximately on line 4—4 of Fig. 2, looking in 55 the direction of the arrows toward the front of the machine;

Fig. 5 is a detached perspective view of the common framework which supports all 60 of the delivery mechanisms, one of these mechanisms being shown in place on the framework; and

Fig. 6 is a cross-section on line 6—6 of Fig. 1, showing how the coin-plate ejects a 65 coin under certain conditions.

The outer casing of the machine may be 70 of any preferred construction. For lack of space, the entire casing is not indicated in the drawings, but only certain portions thereof. The side walls of the casing are 75 shown in the drawings at 1 and 2. These side walls project forwardly at 3 so as to provide sufficient space to accommodate the delivery mechanisms. The grooves or channels 4 of the side walls 1 and 2 are adapted 80 to receive the side members 5 of a supporting frame-work indicated as a whole by F and shown in perspective in Fig. 5. This framework preferably consists of a pair of transverse members 6 and 7 on which are 85 rigidly mounted the side members 5 and the intermediate members 8. The number of intermediate members will, of course, depend upon the number of delivery mechanisms to be embodied in the machine. In 90 the drawings I have illustrated a four-compartment machine having four delivery mechanisms. The side members 5 are shown provided with bottom flanges 9 (see Fig. 4), through which pass suitable fastening devices, such as rivets 10 or the like, whereby the side members are rigidly 95 mounted on the cross-pieces 6 and 7. These cross-pieces are preferably provided with upstanding flanges 11 and 12, which not only strengthen the cross-pieces, but assist 100 in rigidly mounting the members 5 and 8 thereon. From Fig. 5 it will be seen that the members 5 and 8 are provided with notches 13 which firmly engage the flange 11 of the front cross-piece 6. At the rear, the members 5 and 8 abut against the upstanding flange 12 of the rear cross-piece 7. The members 8 are provided with bottom 105 lugs 14 which enter corresponding openings in the cross-pieces 6 and 7, and by means

of these lugs 14 the members 8 are securely riveted on the cross-pieces 6 and 7. The framework F as a whole, is secured in place between the side walls of the casing by suitable fastening devices, such as screws 15, which pass through openings 16 in the front cross-piece 6 into the top of the lower front panel 17 of the casing. This is clearly shown in Figs. 2 and 4.

It will be seen from Figs. 4 and 5 that the members 5 and 8 of the framework F are provided with laterally projecting flanges which are arranged in pairs. These pairs of flanges are marked *a*, *b*, *c* and *d* respectively. Between each pair of these flanges is mounted a delivery mechanism. In Fig. 4, the four delivery mechanisms are, as a whole, indicated respectively by A, B, C and D. The delivery mechanism A is mounted between the flanges *a*, the mechanism B is mounted between the flanges *b*, and so on. As these four mechanisms are alike in construction, it will only be necessary to describe one of them.

Each delivery mechanism has a top plate indicated as a whole by P. This top plate consists of a horizontal front section 18, a horizontal rear section 19, an intermediate vertical section 20, and a downwardly extending front section 21. This plate is preferably formed of a single piece of sheet metal and is bent into the desired shape.

The top plate P of each delivery mechanism carries a casting indicated as a whole by E, which is formed with a pair of side grooves 22. By means of these grooves the delivery mechanism is adapted to be slid into place between a pair of flanges *a*, *b*, *c* and *d*, on the main frame-work F. As clearly seen from Fig. 4, the flanges of the frame-work enter the grooves or channels 22 and thereby support the mechanism in firm position on the frame-work. The inward movement of the delivery mechanism is limited by the front section 21 of the top plate P engaging the front edges of the supporting members 5 and 8 of the frame-work. It will be seen from Fig. 4 that when the delivery mechanisms are in place on the frame-work F, the top plates P are contiguous, and so present practically a single outer plate which forms part of the outer casing of the machine.

The top plate P of each delivery mechanism is provided with a coin-entrance opening 23, which is in alignment with the coin-opening 23^a in the coin-slide 24. Through the vertical section 20 of the plate P projects a hand-operable plunger 24^a, to which the coin-slide 24 is rigidly connected. A slidable block indicated as a whole by K is also rigidly connected with the plunger 24^a. This block is mounted to reciprocate between a pair of arms 25 projecting rearwardly from the plate P. These arms are

securely mounted on the plate P in any suitable manner, as by means of lugs 26 projecting through the top plate and serving as rivets. The arms 25 are provided with a pair of aligned slots 27 in which engage the cross-pieces 28 of the block K, as shown in Figs. 2, 3 and 5. The arms 25 are at their rear connected by a cross-member 29, on which rests the rear end of the rod 30 which carries the return spring 31. The arms 25 rest at their rear end on top of a suitable supporting member 32 rigidly mounted between the side walls of the casing.

The block K of each delivery mechanism has pivoted thereon a suitable ejecting member J. Associated with each delivery mechanism is a magazine M containing the goods or packages to be delivered. I prefer to mount the magazines directly on the arms 25 of each delivery mechanism, as shown in Fig. 2, where the arms 25 are shown provided with recesses 33 adapted to receive the projections 34 at the lower end of the magazine. It will, of course be understood that the upper end of each magazine is suitably held against tilting. In Fig. 2, the lowermost package in the magazine M is indicated at 35, and it will be seen that this package is above the normal position of the ejecting member J. When the plunger 24^a is pushed without a coin having been previously deposited, the ejecting member J is not sufficiently advanced to cause delivery of any goods. When, however, a proper coin is deposited in the coin-opening 23^a of the coin-slide 24 and the plunger 24^a is pushed in, the coin causes the normally locked coin-slide to be released and the plunger is free to be operated to its full extent. As a result, the pivoted ejecting member J is raised at its rear end so as to engage the bottom package 35 and push the same rearwardly out of the magazine, from where it drops down a delivery chute to an opening at the front of the casing (not shown).

In view of the fact that the coin-controlled mechanism by which the ejector J is actuated into ejecting position through the medium of a proper coin does not form part of my present invention, I have not deemed it necessary to illustrate the same in detail, nor to describe the same. In the broad aspect of my invention, any suitable delivery mechanism may be carried by each of the plates P. For the sake of convenience, I have herein shown certain coin-controlled features which form the subject-matter of the Romans and Grover Patent No. 625,123, dated May 6, 1899.

The features of novelty which I claim in the delivery mechanism herein shown, are: First, the means by which the slidable block K is prevented from being tilted upwardly by a downward pressure on the plunger 24^a;

second, the means for causing the coin-slide 24 to eject a coin which is deposited when the coin-slide is out of normal position; third, the means for permitting removal of 5 a deposited coin through the coin-entrance opening 23; and, fourth, guarding against the horizontal insertion of an instrument into the machine.

The upward tilting of the block K, which 10 would cause elevation of the ejector J into ejecting position, is positively prevented by the cross-pieces 28 of the block engaging in the slots 27 of the arms 25. By virtue of this construction, the block K is compelled to 15 travel in a horizontal path.

As shown in Fig. 6, the casting E of each delivery mechanism has secured thereto, by 20 means of screws e, or otherwise, a member indicated as a whole by E'. This member 25 has a front extension f which forms practically a continuation of the front end of the casing E, and a depending rear extension g. The front section 21 of each plate P is provided with a coin-discharge opening h. Should a coin be deposited through the coin-entrance opening 23 when the coin-slide 24 is in inner or actuated position, the coin will 30 drop on to the top of the casting E. When the coin-slide then returns forwardly to normal position, the front edge of the slide will 35 push the coin (see H, Fig. 6) out of the machine through the opening h.

The member E' is provided with an opening k, which is in alignment with the opening or cut-out portion k' of the casting E. The front section 21 of the plate P has an opening m. As seen from Fig. 6, the openings m, k, k', 23^a, and 23, are in alignment, so that an instrument may be inserted into 40 the opening m to lift a deposited coin out of the opening 23, whenever the intending purchaser desires for some reason to get back his deposited coin. The depending extension g of the member E' is so arranged as to prevent 45 the insertion of an instrument horizontally into the machine, whereby tampering with the coin-controlled mechanism back of the guard g is effectively prevented.

The rear section 19 of the plate P of each 50 delivery mechanism is provided with a lug 36 which co-operates with the lower end 37 of the upper front panel 38 of the casing to lock the delivery mechanisms in place when the front panel 38 is in closed position. 55 Only the lower portion of the front panel 38 is shown in the drawings, but it will be understood that this panel extends upwardly to the top of the machine to close the space where the magazines are housed. It is usual 60 to provide a lock at the upper end of the removable front panel 38, so that this panel may be locked in place on the casing. The panel 38 is usually of wood, and the lower edge 37 is preferably a separate piece of metal secured to the wooden portion of the

panel by means of screws 39, or otherwise. The panel 38 is also provided with a hook portion 40 adapted to engage pins or lugs 41 projecting inwardly from the side walls of the casing. It will be clear from Fig. 2 that 70 when the upper front panel 38 is in place, the engagement between the parts 36 and 37 absolutely locks the delivery mechanisms against withdrawal from the machine. Another advantage of this locking means 75 between the delivery mechanisms and the upper front panel 38 is, that unless all of the delivery mechanisms are in proper position on the frame-work F, the lower end 37 of the front panel 38 cannot rest on the rear section 80 19 immediately in front of the lugs 36, in which event it will be impossible to lock the panel 38 in place, because the upper end of the panel would not then go into the casing. I have not illustrated this particular point, 85 because the use of removable front panels on vending machines is well known, and it will therefore be understood how the panel would not fit at the top of the casing if the lower end 37 rested on the lugs 36 instead of on the 90 section 19 of the plates P.

It will be seen from the foregoing that I have provided a multiple-compartment machine in which the separate delivery mechanisms may be removed independently of 95 each other. Should anyone of the mechanisms require repair, it is only necessary to remove that mechanism and insert a new one in its place. Heretofore, in multiple-compartment machines, it has been necessary to 100 send the entire machine, or at least all of the delivery mechanisms, back to the factory for repair, when any one of these mechanisms became disarranged. By my present invention, I obviate this expensive procedure, for the local agent in charge of the machines will carry several extra mechanisms in stock and it would be a simple matter to remove a defective mechanism and replace it by a good one. 105

When the delivery mechanisms are in place on the machine, the plates P act as a single member to close the opening between the lower end 37 of the upper front panel 38 and the top of the lower panel 17. This dispenses with a separate cover plate found in so many machines heretofore constructed. 110

Although I have herein shown and described a certain specific construction, I would have it understood that this has been merely for the sake of illustration and not by way of limitation. It is obvious that changes may be made in the particular structure set forth, without departing from the invention as defined in the appended 120 claims.

This application is a division of my co-pending case, Serial Number 233,194, filed May 8, 1918, and the claims herein are directed to the coin-controlled features. 130

I claim as my invention:

1. In a coin-controlled vending machine, an outer casing, a plate forming part of the front of said casing, said plate being provided with a coin-entrance opening and a separate coin-discharge opening, a slide having a coin-opening to receive the deposited coin and carry the same into operative position, a support beneath said slide for maintaining the deposited coin in the coin-opening of said slide, said support being adapted to receive a coin or check deposited when said slide is out of normal position, hand-operable means for moving said slide inwardly, and means for returning said slide to normal position, said slide being adapted during its return movement to push through said coin-discharge open-

ing any coin or check deposited when the slide was out of normal position.

2. In a coin-controlled vending machine, an outer casing, a plate forming part of the front of said casing, said plate being provided with a coin-entrance opening and a separate coin-discharge opening, a hand-operable member for receiving the coin inserted through said coin-entrance opening and carrying the same into operative position, and means provided on said member whereby a coin inserted into said coin-entrance opening when said member is out of normal position is automatically discharged through said coin-discharge opening during the return movement of said member.

ALBERT D. GROVER.
